UNITED STATES PATENT OFFICE

CHARLES A. BOREHAM, OF COALINGA, CALIFORNIA.

SPRING-CLAMP.

1,097,386.

Specification of Letters Patent.

Patented May 19, 1914.

Application filed March 10, 1913. Serial No. 753,225.

To all whom it may concern:

Be it known that I, CHARLES A. BOREHAM, a citizen of the United States, residing at Coalinga, in the county of Fresno 5 and State of California, have invented new and useful Improvements in Spring-Clamps, of which the following is a specification.

This invention relates to a spring clamp.

Vehicle springs of the laminated or multi-
10 leaf type are often subjected to such severe jolts as to compress the springs far beyond their maximum flexible capacity. The clamp or clip by which the spring is secured to the axle will thus generally act as
15 a fulcrum point about which the spring bends, causing the spring to break at this point.

The object of this invention is to construct
20 a spring supporting clamp, which is pro-
vided with means for yieldingly resisting any excess movement of the spring, so as to prevent breakage at this point.

The invention consists of the parts and the construction and combination of parts
25 as hereinafter more fully described and claimed, having reference to the accompanying drawings, in which—

Figure 1 is a side elevation of a spring, showing the application of the clamp. Fig.
30 2 is a central section of same, partly broken away. Fig. 3 is an end section.

Referring to the drawings: A indicates in general a spring clamp, consisting of two half sections 2 and 3, suitably locked together by bolts 4, for the purpose of securing the several leaf sections 5 forming the spring. Interposed between the spring and the outer ends of the clamp sections 2 and 3 in grooves 6 formed for the purpose,
35 40 is a suitable cushioning material 7, which is provided for the purpose of yieldingly resisting any violent or excess movement of the spring with relation to the clamp.

Springs as commonly used, when subjected to severe jolts which compress the spring beyond its maximum movement, will generally break on the axle or clamp edge by reason of the limited short circular movement at this point. By referring to the
50 drawing it can easily be seen that this objection is practically overcome, as the resili-

ent cushion interposed between the clamp edge and the spring will not only help to absorb the shock imparted to the spring and thus reduce the movement of same, but will 55 also increase the length of the arcual bending movement of the spring with relation to the clamp edge, thus naturally decreasing the breaking tendency of the spring at this point.

60 The resilient cushioning material may be manufactured of rubber or like resilient material, and is adapted to extend across the face of the spring, being held in position against endwise movement by the side extensions 8, formed on the opposite clamp sections, which side extensions also inclose the spring and retain it against side movement.

The clamp here shown is simple and cheap 70 in construction, and takes no more space than the usual forms of clamps generally employed. The life and efficiency of the spring is thus considerably increased by the application of the resilient member, without 75 adding any excess weight or other cumbersome appliances.

I wish it understood that various changes in form, proportions and minor details of construction may be resorted to within the 80 scope of the appended claims, and that I do not wish to limit myself to the specific design and construction here shown.

Having thus described my invention, what I claim and desire to secure by Letters Patent is:

1. The combination with a plurality of concavo-convex leaf springs, of hollow clamps above and below the springs and having inclosing sides meeting approximately midway of the spring pile, said clamps having sockets for uniting bolts upon each side and separated to clasp an axle, and the ends of the clamps having enlarged transverse cylindrical chambers 95 adapted to receive elastic cylinders which are alternately compressed and expanded by the movements of the springs to form shock absorbers.

2. The combination with a plurality of leaf springs, of inclosing clamps, located above and below the springs, said clamping

members being curved outwardly from the
spring surfaces, and having transverse cy-
lindrical channels at the outer ends, cylin-
drical elastic cushions fitting said channels
5 and alternately compressible and expansi-
ble in unison with the vibrations of the
springs.

In testimony whereof I have hereunto set
my hand in the presence of two subscribing
witnesses.

CHARLES A. BOREHAM.
